[57] **CLAIM**

The ornamental design for a vial and solution container connecting device, substantially as shown and described.

DESCRIPTION

FIG. 1 is a perspective view of a vial and solution container connecting device showing my new design;

FIG. 2 is a perspective view of the vial and solution container connecting device shown in FIG. 1 but from the opposite end;

FIG. 3 is a side elevational view;

FIG. 4 is a view similar to FIG. 3 but turned 90° therefrom;

FIG. 5 is an end view taken along line 5—5 of FIG. 4; and

FIG. 6 is an end view taken along line 6—6 of FIG. 4.

FIG. 1.

FIG. 2.

FIG. 3.

FIG. 4.

FIG. 5.

FIG. 6.
